UNITED STATES PATENT OFFICE.

JOSEPH B. MACNAMEE, OF LLANERCH, PENNSYLVANIA, ASSIGNOR TO H. BRINTON COMPANY, OF FRANKFORD, PHILADELPHIA, PENNSYLVANIA, A CORPORATION OF PENNSYLVANIA.

DIAL-ALIGNING DEVICE.

Application filed October 21, 1925. Serial No. 63,941.

To all whom it may concern:

Be it known that I, JOSEPH B. MACNAMEE, a citizen of the United States, residing at Llanerch, in the county of Delaware and 5 State of Pennsylvania, have invented certain new and useful Improvements in Dial-Aligning Devices, of which the following is a specification.

My said invention consists in a dial aligning device for rib knitting machines. As is 10 well understood by those skilled in the art circular rib knitting machines having revolving needle cams are commonly provided with means known as "dogs" for holding the dial 15 in correct angular position relatively to the needle cylinder so as to insure correct positioning of the dial needles relatively to the cylinder needles, each dial needle being midway between two cylinder needles and vice 20 versa. Such devices are commonly objectionable to a certain extent, especially when used with delicate fabrics, by reason of the fact that the fabric must be pulled down between two contacting devices or "dogs" 25 which make "dog marks" in the fabric such marks varying from a very faint streak to a distinct depression or even a torn place in the fabric. These "dog marks" are of course more or less objectionable according 30 to the extent of the injury to the fabric. I have found that by the use of rollers which extend over a considerable number of wales and which are mounted so as to be capable of 35 rocking transversely of the wales, or transversely of the direction of movement of the fabric, the objectionable features of dial and cylinder machines using "dogs" are largely eliminated.

Referring to the accompanying drawings 40 which are made a part hereof and on which similar reference characters indicate similar parts,

Figure 1 is an elevation of a dial and cylinder knitting machine of the type known 45 as a body machine, viewed from the left in Fig. 3, parts being broken away for clearer showing,

Figure 2, a section on line 2—2 of Figure 1,

Figure 3, a horizontal section on line 3—3 of Fig. 1, and

Figure 4, a detail of parts shown in Figs. 1 and 3.

In the drawings reference character 10

indicates a part of the stationary frame of 55 the machine provided at its upper end with a ring 11 on which are supported a plurality of brackets 12 held in place by set-screws 13 bearing against the under side of the ring and set-screws 14 bearing against 60 the said under side and an inclined face 15 on the ring for drawing the brackets securely down to place the set-screws 14 serving to position the brackets by swinging them radially and also to fix them against inward 65 swinging movement. The set-screws are held in locking position by means of lock-nuts 16. A cam ring 17 is mounted for rotation on the ring 11 and a needle cylinder 18 is fixed in relation to the frame inside the 70 cam ring. A dial 19 is supported at the upper verge of the needle cylinder in any conventional or desirable manner and said dial has depending therefrom a bracket 20 with an oil cup 21 serving to keep the oil 75 from the driving shaft of the dial cam cap (not shown) off the fabric as it moves downward through the cylinder. The bracket 20 is connected by a link 22 to a part 23 having at its ends abutments 24 and 25 provided 80 with inclined faces positioned in a manner to be opposed to the direction of rotation of the cam ring and the dial cam cap.

The tubular fabric passes at oposite sides of the tube between the faces of abutments 85 24 and 25 and the adjacent faces of a pair of cylindrical rollers 26 journaled in yokes 27 which are pivotally mounted at 28 in a manner to permit them to oscillate about vertical axes while holding the axes of the 90 rollers substantially in alignment with the planes of the faces on abutments 24 and 25. The oscillation permitted by the pivotal mounting of the yokes enables slight inequalities in the cloth to pass between the 95 rollers and the inclined faces without damage to the cloth and the width of the fabric in contact with said faces and with the rollers is such as practically to eliminate any possibility of "dog marks" in the completed 100 fabric. The means for carrying the yoke comprises a forked support 29 with either one fork or a pair of forks perforated to receive the bolt 28 and another fork with a threaded aperture for a set-screw 30 held in 105 place by a lock-nut 31. The support is pivoted at 32 so that adjustment of the set-screw brings the roller 26 closer to or further

from the abutment on the face 24 and thus determines the pressure of the roller on the cloth.

At the opposite side of the machine is shown a support 33 of somewhat different form, this support being in the form of a bent lever having a bracket 27 mounted at the angle between the two principal arms and having a set-screw 34 in a threaded aperture at the outer end, the lever being pivoted at 35 on a bracket 36 slightly different in form from the bracket 37 on which the support 29 is pivoted. Either form of lever and either form of bracket may be used as desired. The two brackets are connected by a rod 38 to which the brackets are clamped by set-screws 39, the rod 38 serving to hold the brackets against rotation whereby the adjustment of the rollers would be lost.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. In a knitting machine, a needle cylinder, a dial, and connections between them including a cylindrical roller engaging one face of the fabric transversely of the wales, means in contact with the opposite face of the fabric for holding the fabric in engagement with said roller throughout the length of the roller, and supporting means for the opposed fabric-engaging devices permitting a relative rocking movement thereof in a direction transverse to the wales of the fabric, substantially as set forth.

2. In a knitting machine, a needle cylinder, a dial, and connections between them comprising a flat-faced element engaging one face of the knitted fabric, a roller opposite the flat face of said element, and supporting means for the flat-faced element and the roller permitting relative rocking movement thereof in a direction crosswise of the wales of the fabric, substantially as set forth.

3. In a knitting machine, a needle cylinder, a dial, and connections between them comprising an element having an elongated face in position for engagement with the

knitted fabric, a roller engaging the fabric opposite said face, and means supporting the roller for movement about an axis perpendicular to its axis of rotation, substantially as set forth.

4. In a knitting machine, a needle cylinder, a dial, and connections between them comprising an element having an elongated face in position for engagement with the knitted fabric, a roller engaging the fabric opposite said face, means supporting the roller for movement about an axis perpendicular to its axis of rotation, and means for adjusting the roller toward and from said face, substantially as set forth.

5. In a knitting machine, a needle cylinder, a dial, and connections between them comprising an element having an elongated face in position for engagement with the knitted fabric, a roller engaging the fabric opposite said face, a support pivotally mounted on the upright frame of the machine, a pair of arms on said support, a yoke on one of said arms, a roller on said yoke engaging said elongated face, and a screw on the other arm extending outward into engagement with a fixed abutment on the machine, substantially as set forth.

6. In a knitting machine, a needle cylinder, a dial, and connections between them comprising an element depending from the dial said element having flat faces positioned to engage the tubular knitted fabric at opposite sides of the tube, yokes pivotally supported outside the tube, and cylindrical rollers on said yokes engaging the fabric opposite said faces, substantially as set forth.

7. In a knitting machine, a needle cylinder, a dial, and connections between them comprising an element depending from the dial said element having flat faces positioned to engage the tubular knitted fabric at opposite sides of the tube, yokes pivotally supported outside the tube, rollers on said yokes engaging the fabric opposite said faces, and means including a support for each of said yokes pivoted on the machine frame whereby the rollers may be adjusted toward and from said faces, substantially as set forth.

In witness whereof, I have hereunto set my hand and seal at Philadelphia, Pennsylvania this 30th day of September, A. D. nineteen hundred and twenty-five.

JOSEPH B. MACNAMEE. [L.S.]
